UNITED STATES PATENT OFFICE

KARL M. HAMILTON, OF CHICAGO, ILLINOIS, ASSIGNOR TO THE BETTENDORF COMPANY,
OF BETTENDORF, IOWA, A CORPORATION OF IOWA

CAR TRUCK

Application filed July 18, 1927. Serial No. 206,570.

My invention relates to railway trucks of the swing motion type and especially to trucks commonly employed on caboose cars although the use is not limited thereto.

One object of my invention is to provide a truck having an equalized, high spring capacity connection between the side frames and transom.

A further object of my invention is to provide a truck of the swing or lateral motion type wherein connection between the side frames and the transom is effected by integral formations of the side frames and transom and more specifically by telescoping the ends of the transom over the side frames.

Other objects of my invention are to provide a truck wherein all the parts may be assembled and maintained in assembled condition without the use of bolts, rivets or like fastening devices and wherein the truck may be readily assembled or disassembled at any place without special tools.

Other objects will more clearly appear from the description and claims hereinafter following.

In the drawing forming a part of this specification, Figure 1 is a top plan view of a portion of a truck showing my improvements in connection therewith, parts being broken away to prevent crowding on the sheet. Figure 2 is a vertical, sectional view corresponding approximately to the line 2-2 of Figure 1, parts being broken away in this figure also for the same reason. Figure 3 is an end elevational view of the improved truck having my improvements incorporated therein. And Figure 4 is a detail vertical sectional view corresponding substantially to the line 4-4 of Figure 3.

In said drawings, A designates, broadly, the side frames; B the transom casting; C the bolster; D the spring plank; E the bolster supporting springs; and F the transom supporting springs.

In the particular embodiment which I have chosen to illustrate my improvements, the side frames A are of the cast integrally formed journal box type and each comprises an upper arch bar or compression member 50, lower arch bar or tension member 11; in-

tegral journal box 12; and vertical columns 13-13, the latter being spaced so as to leave a central opening 14 for the purpose herein-after described. The arch bars and the columns are preferably each of U-cross section 55 in order to provide great strength although, as will be understood, the sections of these parts may be varied. The side frames also differ from the usual side frame in that the lower arch bar 11 is provided with spring 60 seats 15-15 at widely separated points, said spring seats being, in fact, relatively closely adjacent the journal boxes so as to thereby obtain a maximum spread or distance between the transom supporting springs F-F 65 which are seated on said spring seats 15.

The transom casting B, as shown, preferably comprises two horizontally disposed, elongated main arms 16-16 which are parallel at their outer ends for a short distance 70 as indicated at 16-a and then diverge until the center line is reached as indicated at 16-b and thence converge and are parallel at the opposite ends as will be evident from an inspection of Figure 1. The arms 16 are 75 integrally connected at their respective ends by what may be termed an end section G of the transom. Each end section G is of inverted U cross section as indicated at 17 best 80 in Figure 2 and has forwardly and rearwardly extended arms 18-18, the top webs of the latter being inclined downwardly from the central horizontal portion 19 of the end section G as shown in Figure 3. The width of the U-section is such as to adapt the same to closely telescope over the upper arch bar 10 of the side frame, said upper arch bar being so telescoped for substantially its entire length, that is, from points closely adjacent the journal boxes 12, as indicated in 85 Figure 3. In this manner, it is evident that endwise movement of the transom relative to the side frame is limited by the telescoped engagement of the end sections G of the transom casting with the side frames. 90

Each arm 18 of the transom, at its end, is provided with semi-bearings 18-a cooperable with a spring cap 20 seated on the top of the corresponding spring F so that the arms 18 of the transom casting are supported 100

by the springs F and at the same time a slight rocking or tilting movement between the same and the spring caps is permitted.

The parts will be so designed that the upper 6 web portion of the end sections G of the transom casting will be normally spaced from the upper surface of the upper arch bar about two inches, thus allowing for up and down movement of the transom relative to 10 the side frames.

At the center, each end section G of the transom casting is provided with two depending arms 21-21, the latter having vertical guiding faces 22-22 which are adapted

15 to cooperate with corresponding guide flanges 23-23 provided on the columns 13 so as to thereby restrain the transom casting to vertical movements relative to the side frames. The end section G may be reinforced around the opening defined by said

20 depending side arms by suitable flange sections as indicated at 22-a best in Figure 2. The depending arms 21 may further be braced with respect to the remainder of the 25 castings by webs 24.

The transversely extending main arms 16 of the transom casting are preferably of hollow box-like cross-section as indicated at 16-c in Figure 3.

30 At their ends, the arms 16 of the transom casting are slotted as indicated at 26 and provided with semi-bearings to accommodate the spring plank hangers 27 with their supporting pins 28. The lower ends of the

35 hanger links 27 are connected by a cross link 29, the latter supporting a spring plank bearing plate 30 on which the spring plank D is mounted, the connection between the same being detachable by means of lugs 31 formed

40 integrally with the plate 30 and extending through suitable perforations in the spring plank D. At each end of the spring plank the spring seats 32 are provided on which are seated the elliptic plate springs E, the latter

45 in turn supporting the ends of the bolster C, thus providing for a swing motion type of truck as will be obvious to those skilled in the art. The details of the bolster C may be varied and I do not deem it necessary to enter into a detailed description thereof in this 50 application.

With my improved arrangement, it is evident that all of the parts may be assembled and maintained in assembled condition without the aid of bolts, rivets or like fastening devices. The transom casting is assembled with the side frame by simply telescoping the end sections G over the side frames as will be obvious. By providing forwardly

60 and rearwardly extending arms on the end sections of the transom casting and supporting them by the springs F as shown, the side frames are enabled to carry a much heavier load per given weight, the transom is supported in an equalized manner and an easier

riding truck thereby provided. This, in combination with the laterally movable bolster, yieldingly supported from the transom affords an exceptionally easy riding truck, making the same particularly adapted for caboose cars. It will be noted also that the elliptic springs E are extended in part through the openings 14 of the side frames, thus allowing of the use of large sized elliptic springs and a spring plank of proper length. Another advantage of my improvements, as will be apparent from an inspection of Figure 3, resides in the fact that, upon failure or undue set of either spring F, the displacement or tilt of the transom casting will be comparatively small since the corresponding arm 18 of the transom casting will drop down to engagement with the corresponding adjacent section of the upper arch bar and there would still remain a cushioned support between the transom and the side frame.

I have herein shown and described what I now consider the preferred manner of carrying out my invention, but the same is merely illustrative and I contemplate all changes and modifications that come within the scope of the claims appended hereto.

I claim:

1. In a truck, the combination with side frames having tension and compression members and guide columns extending therebetween and defining a window opening; of a transom, said transom having end portions telescoping over the upper portions of said compression members of the side frames and being cut out to leave said window openings substantially unobstructed.

2. In a truck, the combination with side frames having tension and compression members and guide columns extending therebetween and providing window openings; of a one piece cast transom, the latter having end sections shaped so as to telescopically fit compression bars of the side frames and to be disposed substantially out of line with said window openings.

3. In a truck, the combination with side frames having tension and compression members and guide columns extending therebetween; of a transom having the ends thereof telescoped over said side frames and having a cut-out portion; a spring plank supported from said transom; a bolster; and springs interposed between said plank and bolster and extending into the cut out portions of said transom.

4. In a car truck, the combination with side frames having tension and compression members and guide columns extending therebetween; of a transom having arms extending longitudinally over the top of and yieldingly supported by said side frames at points distant from the center of the latter on springs carried by said tension members; a

spring plank supported from the transom; a bolster, elliptical springs between said bolster and said spring plank and extending longitudinally of the bolster and projecting through the side frames between the guide columns.

5. In a car truck, the combination with side frames each having tension and compression members, guide columns extending therebetween and spaced spring bearing seats on said tension member; a transom having, at each end, integrally formed, oppositely extending arms of channel shape disposed lengthwise of and telescoped with said compression members; and spring means interposed between each said seat and corresponding transom arm.

6. In a truck, the combination with side frames; of a cast member comprising spaced beams extending between said side frames, said beams connected at their ends by end sections open on the bottom and said sections telescoping over said side frames.

7. In a truck, the combination with side frames having tension and compression members and guide columns extending therebetween; of a cast member extending between said side frames, said member having end sections open on the bottom and said sections telescoping over the compression members of said side frames, said members and side frames having cooperable vertically extending guiding means; and springs interposed between said side frames and member.

8. In a car truck, the combination with cast side frames having compression and tension members, guide columns extending therebetween and integral journal boxes; of a transom telescoped over said side frames, said transom having forwardly and rearwardly extended arms; springs on said tension members of said side frames and cooperable with the end portions of said transom arms; and a bolster supported for lateral movement relative to said transom.

9. As an article of manufacture, a transom casting for trucks comprising: two horizontally disposed, spaced arms and integral connecting sections at their ends, said connecting sections having arms projecting forwardly and rearwardly of said horizontally disposed arms, said sections being open on the bottom and being cut out centrally to provide clearance space when used with a truck.

10. As an article of manufacture, a transom casting for trucks comprising: two horizontally disposed arms arranged to extend transversely of the truck when the transom is in place, two end sections arranged to extend lengthwise of the truck, said end sections integrally uniting said arms and extending forwardly and rearwardly thereof, each end section being of approximately inverted U cross-section and thereby

adapted to be telescoped over truck side frames.

11. In a car truck, the combination with cast side frames provided with centrally disposed openings; of a transom having the ends thereof telescoped over said side frames; relatively widely separated springs interposed between each side frame and corresponding adjacent end of the transom; a spring plank suspended from said transom; a bolster; and elliptic plate springs interposed between the bolster and spring plank, portions of said plate springs being extended outwardly through the central openings of said frames.

12. In a car truck, the combination with cast side frames having compression and tension members and columns provided with vertical guides thereon; of a cast transom having hollow end sections, the latter telescoping over said side frames, each of said end sections having vertically disposed guiding flanges cooperable with those of the side frames.

13. In a car truck, the combination with side frames, each including a tension member and a compression member and guide columns; of a transom having spaced beams and integral connecting sections having arms projecting longitudinally of said side frame and of channel-shape to fit over the compression members; spring means interposed between the end portions of said arms and the tension members of said side frames; a spring plank swingingly suspended below said transom; a bolster disposed between the spaced beams of said transom; and additional spring means interposed between the end portions of said spring plank and the corresponding portions of said bolster.

14. In a truck, the combination with the side frames thereof each comprising a compression and tension member spaced apart adjacent their central portions and converging adjacent their ends, and guide columns disposed between said tension and compression members in spaced relation adjacent the central portions thereof; a transom extending between said side frames and having means cooperating with said columns for guiding the transom; arms at the ends of said transom extending lengthwise of said side frames yieldable means interposed between the ends of said arms and the related side frame; a bolster; a spring plank swingably supported from said transom, and elliptical springs interposed between said bolster and said spring plank adjacent the respective ends of the same, said elliptical springs projecting between the guide columns of the respective side frames and between the portions of the transom co-operating with said guide columns.

15. In a truck, the combination with side frames each having a tension member, com-

- pression member and guide columns, integrally formed; a transom; means for guiding said transom with reference to each of said side frames; yieldable means interposed between the respective ends of the transom and the adjacent side frame; a spring plank swingably supported from said transom; and elliptical springs interposed between the opposite ends of said spring plank and bolster, said springs extending outwardly between said guiding means and the guide columns of each frame.
16. In a truck, the combination with side frames each having a compression and tension member converging adjacent their ends, and spaced centrally disposed guide columns extending between said compression and tension members; a transom co-operating with said side frames and being provided with spaced extensions defining an opening registering wth the opening between said guide columns; means for yieldably supporting said transom upon said guide frames; a bolster; means swingably supported from said transom; and elliptical springs interposed between said swingable means and said bolster and projecting through the registering openings between the extensions on said transom and said guide columns.
17. In a truck, the combination with side frames, each comprising compression and tension members converging adjacent their ends and being separated by centrally arranged spaced guide columns; a transom having its opposite ends projecting across the plane defined by said compression and tension members and having cut-out portions in said ends affording clearance in line with the space between the guide columns of said frames; means carried by said side frames for yieldably supporting said transom; a spring plank; spring plank hanger links swingably supporting said plank from said transom; a bolster; and yieldable means interposed between said bolster and said spring plank, said yieldable means being in the form of elliptical spring means extending outwardly between the guide columns and through the space afforded for clearance by the cut-out portions of said transom.
18. In a truck, the combination of side frames provided with journal boxes, each of said side frames having guide members thereon spaced from said journal boxes, a transom disposed between said side frames and having guides cooperating with said guide members to restrict the transom to vertical movement relatively to said frames, arms laterally extending from the ends of said transom in opposite directions adjacent the side frames, resilient supporting means disposed between the ends of said arms and said frames, a bolster, a spring plank swingably mounted on said transom, and resilient supporting means disposed between said
- spring plank and said bolster for supporting said bolster, said last named resilient means comprising elliptic springs, said springs extending between said guide members and guides.
19. In a truck, the combination of side frames having journal boxes, spaced guide members on said side frames spaced from said journal boxes, a transom having members co-operating with said guide members and defining an opening, means disposed between said transom and said side frames for supporting said transom, a bolster, a spring plank, means for movably supporting said spring plank from said transom, and means interposed between said spring plank and bolster and extending between said guide members and second named members for resiliently supporting said bolster.
20. In a transom, the combination of a member, yokes provided at the ends thereof, said yokes being provided with side portions adapted to cooperate with a side frame member and central connecting portion, said yokes and member having vertical guides thereon, side portions having spring-positioning means on the bases thereof.
21. In a truck, the combination of side frames having upper and lower chords, spaced column guides between said chords, transom, transom yokes having columns slidably engaging said guides, resilient members supported on the frame lower chord and supporting said yokes, a bolster, a spring plank, and supporting members between said bolster and spring plank and disposed to partially project beyond said frames between the transom columns.
- In witness that I claim the foregoing I have hereunto subscribed my name this 13th day of July 1927.
- KARL M. HAMILTON.
